SHIRT TYPE GARMENT

Lola R. Spare, Pasadena, Calif.

Application September 1, 1950, Serial No. 182,707

7 Claims. (Cl. 2—115)

1

This invention relates to articles of apparel and particularly to improvements in garments of the shirt or blouse type.

It is highly desirable in shirts, blouses and similar upper garments, particularly those which are made for use as sports wear, that they be designed to permit maximum freedom of movement of the body. This desirable condition is especially important in a shirt-type garment which is employed as the upper part of a pajama. To achieve this result, such garments are frequently made relatively large so as to provide greater fullness so that ease of motion of the body therein is attained. Various expedients have been utilized for producing such fullness, one being to make the garment of over-sized proportions. In other cases, the material is Shirred and gores or other pieces are inset to provide the necessary fullness.

It is well known that stretchability of the fabric is an important factor to be considered when designing a garment which is to afford maximum comfort for the wearer since "stretch" or "give" of the fabric in response to body movements avoids binding and restraining of such movements. For this reason, knitted fabric having two-way stretch has been employed extensively for the purpose, such fabric affording maximum elasticity and stretchability, while providing a close fit of the article of apparel on the body of the wearer. While such knitted fabric is used quite extensively, garments of woven fabric are preferable for the reason that garments of woven fabric retain their shape and may be ironed readily to effect a neater appearance. As explained before, it has heretofore been thought that garments of woven material may provide adequate freedom of movement only when they are made over-sized, shirred or provided with suitable insets. As will be apparent, the cost of producing such a garment is necessarily high due to the large amount of fabric and the extra sewing operations involved.

It is therefore an important object of this invention to provide an article of apparel of the shirt or blouse type which is made from woven fabric and which allows full freedom of movement of the body.

Another object is to provide a garment of the character referred to, in which at least the front portion thereof is cut on the bias of the woven fabric so as to effect two-way stretch, that is, stretch in both horizontal and vertical directions. By this provision, the fabric will "give" or yield to body movements so that maximum

2

flexibility and comfort are assured. In addition, the use of a bias-cut front results in a great saving of material and this is an important consideration. Since the bias-cut front may be cut smaller than heretofore, and requires no special fitting of inset pieces, the time required to sew the pieces is minimized and this further reduces the over-all cost of the garment.

At the present time garments of the sport shirt type have two-part fronts, the parts meeting at the vertical center and being separably connected by buttons, slide fasteners or other fasteners. In other garments of this character the front panel is made in one piece and an entrant opening extends diagonally downwardly and laterally from the neck opening to facilitate donning and removal of the garment over the head of the wearer. In such a garment, a slide fastener is employed for closing the entrant opening. Since the material is cut on the straight run of the weave and the entrant opening extends diagonally thereof, the edges of this opening are necessarily bias-cut. For this reason, it is extremely difficult to sew the tapes of the slide fastener to the fabric and puckering and fraying of the edge portions of the material invariably result. It is thus another object of the present invention to avoid the deficiencies of prior garments having diagonal entrant openings by providing a garment of this class in which the weave of the cloth is so disposed that the diagonal entrant opening extends parallel to the weave, this object being attained by making the front panel in at least two sections each cut on the true bias of the weave, the meeting edges of the fabric sections forming the sides of the entrant opening having sewed thereto the tapes of the slide fastener. By this structure, the front panel of the shirt or like garment is stretchable in both lateral and vertical directions and, since the slide fastener itself is flexible and distortable, the material can be stretched across the separable opening in said directions. It is thus seen that by this invention the front of the shirt is fully stretchable, even across the slide fastener, so that maximum comfort and freedom of movement of the body are attained.

Another object is to provide a garment of the type specified which may have pointed inset pieces forming the shoulders of the garment, said pieces being cut on the bias of the material and thus affording stretch at these portions of the garment.

A further object is to provide a garment of the class indicated in which the rear panel of

the garment is formed with V-shaped notches adjacent the lower ends of its vertical side edges and in which the front panel has pointed projections at its corresponding portions, the projections being disposed in said notches and sewed to the edges of the same. By this means, the lower ends of the side seams of the garment are in the form of zig-zags and, since the projections are cut on the bias, two-way stretch of the same is possible so that strain, which frequently occurs at these portions of the garment and causes tearing of the cloth or pulling out of the seam stitches, is entirely avoided.

Further objects of the invention will appear from the following specification and from the drawings which are intended for the purpose of illustration only, and in which:

Fig. 1 is a front view of a garment of the sport-shirt type made in accordance with the present invention;

Fig. 2 is a rear view of the same;

Fig. 3 is a composite pattern of the several components of the shirt, illustrating the manner in which the pieces are cut from a single piece of woven fabric to obtain the bias-cut and the straight-cut pieces;

Fig. 4 is a side view of the bottom portion of one side of the shirt, illustrating a novel form of side seam; and

Fig. 5 is a fragmentary front view of the upper portion of a shirt or blouse of alternative construction.

Referring to the drawings in detail, the sport shirt shown by way of example is embodied in a particular design to provide a pleasing appearance but it is to be understood that the shirt may take other forms, within the scope of this invention. The shirt includes a substantially rectangular back panel 11 and a multi-part front panel 12 of generally rectangular shape, the vertical side edges of the panels being joined together in side seams 13. The upper side portions of the panels 11 and 12 are provided with arcuate cut-out portions 14 and 15 which, when the panels are sewed together, provide armholes or sleeve openings. Sleeves 16 and 17, of conventional form, have their upper ends sewed into the armholes, the sleeves shown being of the short type.

Connected to and extending between the upper ends of the panels 11 and 12 is a shoulder piece 19 which has an edge 20 sewed to the upper edge of the back panel 11 at 21 and edges 22 sewed to the upper edges of the front panel at the sides of the neck opening, as indicated at 23. A curved cut-out 24 of the shoulder piece 19 forms the back portion of the neck opening of the garment. A collar 25, composed of two pieces 26 and 27 sewed together, has an edge 28 which is sewed to the arcuate edges forming the neck opening. As shown in Fig. 1, triangular extensions of the front panel 12, adjacent the neck opening are folded outwardly to provide lapel portions 30 which are sewed to edges 31 of the collar 25. Conventional facing pieces 32 have triangular portions 33 which overlie the front faces of the lapel portions 30 and to which they are sewed along the edges thereof. The facing pieces 32 have curved edges 34 which are sewed to the inner edge of the collar 25 at 31.

In accordance with the present invention, the front panel 12 is composed of at least two components, the present drawings showing the panel as made up from three sections 40, 41, and 42. The lower panel section 40 consists of a lower rectangular portion 43 and an upper pointed

portion 44, the angle included between the side edges 45 and 46 of the upper portion being preferably 90°. The panel section 40 has side edges 47 which form part of the side seams 13 of the garment.

The panel sections 41 and 42 are identical in shape and size, each being of trapezium shape. The sections 41 and 42 have side edges 50 and 51 which are sewed to the corresponding side edges of the back panel 11 along the seam 13. The sections also have edges 52 and 53 which are sewed to the edges 22 of the shoulder piece 19 and have arcuate edges 54 which form part of the neck opening and to which the collar 25 is sewed. The sections 41 and 42 have third sides 56 and 57, respectively, each of which forms the edge of one of the lapels 30 (Fig. 1). The fourth sides 59 and 60 of the respective sections 41 and 42 are adapted to be connected to the respective sides 45 and 46 of the bottom section 40.

In accordance with the invention, the side 60 is sewed to the side 46 of the bottom section 40. The side 59 of the upper section 41, however, is separably connected to the side 45 of the bottom panel throughout the greater portion of its length by means of a slide fastener 65. The fastener 65 is of conventional form and has tapes which carry the fastener elements, the tapes being sewed to the adjoining edges 59 and 45. In the embodiment of the invention disclosed in the drawings, the slide fastener extends diagonally from the lower end of the neck opening toward a side seam 47 and terminates inwardly from said seam. In other cases, however, the slide fastener may extend outwardly to the side seam.

Referring now to Fig. 3, it will be observed that all the components of the shirt-type garment shown in Figs. 1 and 2 may be readily cut from a single piece of woven fabric. It is also to be observed that by laying out the pieces in the compact arrangement disclosed the several components may be cut from a piece of cloth of relatively small area. For example, by arranging the patterns as shown, all the components of a man's shirt of medium size can be cut from a piece of fabric which measures approximately 36" x 50", this representing a large saving of material.

It is extremely important to note that the warp and filling or woof threads of the fabric respectively extend lengthwise and transversely of the piece of woven material, as indicated by the crossing arrows 70 and 71 at the upper left-hand corner of the fabric. By arranging the various patterns as shown in Fig. 3, the pieces 11, 16, 17, 19, 26, 27 and 32 are cut on the straight run of the weave.

The front panel sections 40, 41 and 42, on the other hand, are cut on the true bias of the weave. Consequently, when these sections are connected as shown in Fig. 1, the entire front panel 12 is arranged on the true bias of the fabric. Since the diagonal edges 46, 60 and 45, 59 extend at angles of 45° with respect to the vertical and horizontal, it is apparent that these edges extend parallel to the weave of the fabric and fraying or puckering of the material along these edges is minimized. This is especially important from the standpoint of manufacture since by the present invention the slide fastener tapes can be conveniently sewed in place in a minimum of time to produce smooth, unpuckered lines of joiner.

Assuming that the garment is to be donned by a person, the slide fastener 65 is first opened to provide a side opening which forms, in effect, a

continuation of the neck opening to facilitate sliding the garment over the head and onto the body with the arms of the person disposed in the arm elements of the garment. After the shirt has thus been donned, the slide fastener is operated to close the opening so as to retain the shirt in place on the trunk of the wearer. When the wearer engages in sports or other physical exercise and the shirt is subjected to pulling, twisting or other stresses, the entire front panel 12 is adapted to yield to the body movements. That is to say, due to the fact that the panel 12 is cut and arranged on the true bias of the weave, it possesses a high degree of stretchability and elasticity so that it is capable of distortion, particularly in vertical and lateral directions. Consequently, the highly desirable stretchability is attained with the use of woven fabric and without making the garment over-size to allow freedom of movement of the body. It is extremely important to note that, since the slide fastener is flexible and is arranged in a line which is parallel to the weave of the bias-cut sections of the front panel, the fabric of the front panel can be stretched both vertically and horizontally across the slide fastener so that the use of the separable fastener does not affect or impair the ability of the fabric to yield to body movements.

It will be apparent that other fastener means, such as buttons, snap-fasteners, etc., might be employed in lieu of the separable slide fastener 65 disclosed in the drawings. It is also obvious that the front panel sections 49 and 42 may, if desired, be cut from a single piece of woven fabric although this will result in an unsymmetrical appearance and necessitate the utilization of a larger piece of fabric from which the several components of the shirt or blouse are cut.

While only the front panel 12 of the improved garment is shown herein as cut on the true bias of the weave, it will be understood that the back panel 11 also may be so cut to attain even greater stretchability, although this has been found to be unnecessary for the reason that adequate freedom of body movement is produced by the construction herein disclosed. It has been determined that when either or both panels are cut on the bias and the lower end of the bias-cut panel is tucked under the belt of trousers or the waistband of pajamas, the fabric stretches or "gives" vertically and thus there is no tendency for the panel or panels to pull out from under the belt or waistband.

Referring now to Fig. 4, this invention contemplates means for minimizing the tendency of the garment to tear at the lower ends of the side seams due to strain imposed thereagainst. In this embodiment, the vertical side edges of the back panel 11 are provided with V-shaped notches 70 at their lower ends. The vertical side edges of the front panel 12 are provided with pointed projections 71 which are adapted to be disposed in the notches 70. During the assembling of the front and back panels along the seam 13, the corresponding diagonal edges of the notches 70 and the projections 71 are seamed together, as indicated by the line of stitches 72. It will be apparent to one skilled in the art that the triangular inset or projection 71 is stretchable in both vertical and horizontal directions due to the fact that it is cut on the bias of the weave. Consequently, when pulling forces are applied against the seam portions of the garment, the fabric will yield readily to prevent tearing of the material or displacement of the seam stitches.

Fig. 5 illustrates an alternative form of construction of a shirt or blouse. In this embodiment of the invention, the garment is provided with elements 80 which have tubular portions 81 forming the arms, and integral, pointed extensions 82, the edges of which are sewed to the upper sloping edges of the front and back panels, only the front panel 83 being illustrated. It is thus seen that by this construction a single piece of fabric provides both an arm and a shoulder portion of the garment. It has been found advantageous to cut the elements 80 on the bias of the weave so as to effect stretchability and elasticity at the shoulder portions of the garment.

It will be understood by those versed in the garment art that various modifications might be made in the construction of the garment herein disclosed without departing from the spirit of the invention.

I claim as my invention:

1. A shirt-type garment of woven fabric, comprising: a back panel; and a front panel, said back and front panels defining between them a neck opening and arm openings, said panels being seamed along their vertical side edges, said front panel being composed of at least two sections separably connected along a diagonal line, said sections being cut on the bias of the weave with said diagonal line extending parallel to said weave so as to allow stretch of said front panel in both vertical and horizontal directions across said diagonal line.

2. A shirt-type garment of woven fabric, comprising: a back panel; and a front panel, said back and front panels defining between them a neck opening and arm openings, said panels being seamed along their vertical side edges, said front panel being composed of at least two sections having adjoining edges permanently joined along a diagonal line, said sections being cut on the bias of the weave with said diagonal line extending parallel to said weave so as to allow stretch of said front panel in both vertical and horizontal directions across said diagonal line.

3. A shirt-type garment of woven fabric, comprising: a back panel; a front panel, said back and front panels being seamed along their vertical side edges and defining between them a neck opening and arm openings, said front panel being composed of at least two sections each cut on the bias of the weave and each having an edge extending parallel to said weave and diagonally with respect to said front panel, said edges substantially meeting in a diagonal line; and interengaging separable fastening means on said edges by which said sections can be separably and flexibly joined along said diagonal line, said front panel being stretchable in both vertical and horizontal directions across said diagonal line.

4. A shirt-type garment of woven fabric, comprising: a back panel; and a front panel, said back and front panels being seamed along their vertical side edges and defining between them a neck opening and arm openings, said front panel including a lower section having an upper pointed end providing upper diagonal edges, a first upper section having a lower diagonal edge joined to one of said upper diagonal edges in a diagonal seam, and a second upper section having a lower diagonal edge separably connected to the other of said upper diagonal edges and providing a diagonal connection, all of said sections meeting at the vertical center of said front panel, all of said sections being cut on the bias of the weave, said diagonal seam and said diagonal separable con-

nection extending parallel to the weave so as to allow both vertical and horizontal stretch of the fabric across said diagonal seam and said diagonal connection.

5. A shirt-type garment of woven fabric, comprising: a back panel; and a front panel, said back and front panels being seamed along their vertical side edges and defining between them a neck opening and arm openings, said front panel including a lower section having an upper pointed end providing upper diagonal edges, a first upper section having a lower diagonal edge joined to one of said upper diagonal edges in a diagonal seam, and a second upper section having a lower diagonal edge separably connected to the other of said upper diagonal edges and providing a diagonal connection, all of said sections meeting at the vertical center of said front panel adjacent said neck opening, and all of said sections being cut on the bias of the weave, said diagonal seam and said diagonal separable connection extending parallel to the weave so as to allow both vertical and horizontal stretch of the fabric across said diagonal seam and said diagonal connection.

6. A shirt-type garment of woven fabric, comprising: a back panel; and a front panel, said back and front panels being seamed along their vertical side edges and defining between them a neck opening and arm openings, said front panel including a lower section having an upper pointed end providing upper diagonal edges, a first upper section having a lower diagonal edge joined to one of said upper diagonal edges in a diagonal seam, a second upper section having a lower diagonal edge disposed adjacent and extending alongside the other of said upper diagonal edges, and a separable, flexible, slide fastener connected be-

tween said adjacent diagonal edges and normally retaining said diagonal edges in juxtaposition, all of said sections meeting at the vertical center of said front panels, and all of said sections being cut on the bias of the weave, said diagonal seam and said diagonal separable edges extending parallel to the weave so as to allow both vertical and horizontal stretch of the fabric across said diagonal seam and said slide fastener.

10 7. A shirt-type garment of woven fabric, comprising: a back panel; and a front panel, said back and front panels being seamed along their vertical side edges and defining between them a neck opening and arm openings, one of said panels being cut on the bias of the weave and the other being cut on the straight run of the weave, each vertical side edge of the non-bias cut panel having a notch at the intersection of the vertical edge and the lower edge of the panel, each vertical side edge of the bias-cut panel having a lateral projection of the same contour as said notch and inset therein, the edges of said projection being sewed to the corresponding edges of said notch.
